UNITED STATES PATENT OFFICE.

ARTHUR DICKERSON, OF SALT LAKE CITY, UTAH, ASSIGNOR TO MECHANICAL DEVELOPMENT COMPANY, OF SALT LAKE CITY, UTAH, A CORPORATION.

CYLINDER-BORING MACHINE.

Application filed January 31, 1921. Serial No. 441,206.

To all whom it may concern:

Be it known that I, ARTHUR DICKERSON, a citizen of the United States, residing at Salt Lake City, in the county of Salt Lake 5 and State of Utah, have invented certain new and useful Improvements in Cylinder-Boring Machines, of which the following is a specification.

My invention relates to tools and holders 10 therefor, and has for its object to provide a cutting tool and a holder which is secured on an engine block whereby the cylinders of an internal combustion engine may be quickly and efficiently trued up and bored 15 out without removing the engine from its position on the frame of a road vehicle, such as automobiles, trucks and tractors.

These objects I accomplish with the device illustrated in the accompanying drawings 20 in which similar letters and numerals of reference indicate like parts throughout the several views and as described in the specification forming a part of this application and pointed out in the appended claims.

25 In the drawings, in which I have shown a substantial embodiment of my invention, Figure 1 is a side elevation of the device. Figure 2 is an elevation showing the device in place on the engine of an automobile 30 somewhat reduced in size from the other views. Figure 3 is a longitudinal section of the hollow shaft showing the cutting tools with the adjusting elements therefor in elevation, parts cut way. Figure 4 is a 35 view in perspective, somewhat enlarged as to the other figures, of the cutting face of the tool with the other dimensions shown diagrammatically. Figure 5 is an elevation of the cutting tool, showing one corner 40 thereof.

In boring out or in trueing up the cylinders of engines used on automobiles, trucks and tractors it is highly desirable 45 in order to save time, that the work be done without having to remove the engine block from the frame of the vehicle, but one of the difficulties has been to provide a tool holder which may be adjusted and rigidly held in 50 position relative to the cylinder to be worked on, and to provide one which may be operated without using the common bench or machine lathe, as well as to overcome the other difficulty of providing a cutting tool which may be adjusted to cut just

the required amount of material to true up 55 the cylinder.

The present invention overcomes such difficulties and consists of an adjusting standard A, having a central longitudinal bore and within which is carried the clamping bolt B. The said bolt is threaded at each end and provided with nuts screwed thereon, with its lower portion passed through one cylinder. A clamp plate 1 is carried on said bolt B to engage the under side face of the cylinder block C of the engine and is the means used by me to hold my device rigidly in place while boring out the adjacent cylinder. The lower end portion of said standard A is given a square 70 form, while the main portion of the standard is cylindrical, thus throwing out on each lower corner an integral lug 2, which lugs are bored and internally threaded to hold the tap screws 3. Each of said squared 75 portions of said standard is slotted as at 4 to provide another lug 5 against which the lower end of the tap screw 3 bears, and the material is such that the lug 5 may be 80 slightly sprung to adjust the boring shaft D and direct the cutting tools. Integral bracket arms E and F are also formed on said standard A. The free end of the bracket arm F is given a collar form as at 6 and acts as a bearing for and carries the 85 lower end portion of the boring shaft D. The free end of the bracket arm E is also given a collar form, as at 7, and is internally threaded to engage the threads of the said 90 boring shaft D and also act as a bearing for 95 said shaft. Each of said collars 6 and 7 is provided with extended lug portions, and is slotted through said lug portions to the interior of the collar. Bolts with nuts thereon are carried in holes bored in said lug portions 6' and 7' respectively to take up any 100 wear which may take place by the operation of said boring shaft D. The boring shaft D is hollow and has one portion externally threaded, as at 8, to engage the threads in the said collar 7, and is the means used to 105 advance and hold the cutting tool to its work. A crank handle 10 is fastened on the upper end of said holding shaft D to rotate said shaft, while on the lower end of said shaft is secured the tool holder 11. The said tool holder is cylindrical in shape and is diametrically bored or provided with

a square opening 12 within which is carried the special cutting tools 13. A bearing plug 14 is fastened in the said holding shaft D near and partially within said tool holder 11, and two openings are bored in said bearing plug to carry the lower ends of two tool adjusting rods 15 and 16. Another bearing plug 17 is fastened in the upper end of said holding shaft D, and which plug 17 is also bored and internally threaded to carry the upper ends of said adjusting rods 15 and 16. The upper end portion of each of said rods 15 and 16 is externally threaded to engage the threads 15 of said plug 17, and the extreme end portions of said rods 15 and 16 are shaped to be engaged by a wrench to rotate and move said rods longitudinally. The lower end of each of said rods is tapered and given a 20 conical form to engage the angled end of the cutting tool, whereby said tool may be adjusted to its work. I have provided a special cutting tool G, two of which are used in the device, and each consists of a 25 squared rod of steel having one end cut at an angle, as at 18, against which the conical end of one of the rods 15 or 16 bears, while the other end is first given a cylindrically curved form, as shown at 19, and 30 then a convex cut as at 20, cutting away a portion of the form 19, and leaving a cutting edge 21 which is curved in two ways and angled in its general direction from opposite corners of the tool, to give the tool 35 a draw cutting effect and prevent its vibration. The tool is backed off in grinding, as shown by the faces 22 and 23. With a tool thus formed and constructed it is interchangeable, and may be used to cut when the 40 said shaft is rotated in either direction by turning the tool one-half over; thereby leaving the general direction of the cutting edge 21 on the same angle, that is, from the lower left hand corner to the upper right hand corner and with the convex curve 20 upward 45 when used as right hand and downward when used as left hand.

The operation of my device is as follows: The upper face of the engine block is bared 50 and the device is set over one of the cylinders with the squared end of the standard A resting on said upper face and the clamp plate 1 engaging the lower end of the same cylinder. The nuts on the rod B are turned 55 up to fasten the device rigidly in place and with the holding shaft D in alinement with one of the cylinders to be bored. With the cutting tools in place, one positioned to cut when said shaft is turned toward the right 60 and the other positioned to cut when the shaft D is turned toward the left, the device is operated by turning the shaft D toward the right and by noticing where the

tool is cutting it can be readily seen whether the shaft D is in alinement with the cylinder under treatment, and if not, by turning the tap screws 3 this adjustment may be quickly made. Then by rotating the said shaft D toward the right a cut may be made through said cylinder, and desiring to cut when the shaft D is being raised the right hand cutting tool is released by withdrawing its adjusting rod 15 or 16 as the case may be, and turning down the other of said rods, which is in engagement with the left hand cutting tool G. This will allow the left hand tool to cut its way as the shaft D is raised. The operation of the two tools G, one cutting as the shaft descends and the other cutting as the shaft ascends, gives the rapidity of work desired. When one cylinder has been trued up, the device may be fastened through that cylinder and the adjacent cylinder cut out as above described. I thus provide a new and novel standard for rigidly holding a hollow shaft in alinement with the cylinder of an engine and novel bearing collars which will allow the said hollow shaft to be moved longitudinally through them, and within which hollow shaft are new adjusting rods by which cutting tools are moved radially within a new and novel tool casing or holder, with a new and novel tool specially adapted to be used as a part of the device.

Having thus described my invention I desire to secure by Letters Patent and claim:—

1. A cylinder boring machine comprising a standard having integral bearing arms for a boring bar, lugs projecting from the lower portion of said standard each having a threaded hole therein; other lugs integral with said standard and spaced from the perforated lugs; tap screws with the threads thereon meshing with the threads in the hole of the first mentioned lugs, whereby the upper of said bearing arms may be adjusted laterally to direct the said boring bar.

2. A cylinder boring machine comprising a standard having integral bearing arms at each end thereof, and in which arms a boring bar is operated; integral portions of one end of said standard extended as a base; each of said extensions slotted in transverse direction as to said standard; and tap screws operated through one portion of each extension lug and seating against the adjacent portion of the same lug to spring said adjacent portion and thereby adjust the direction of said boring bar.

In testimony whereof I have affixed my signature.

ARTHUR DICKERSON.
